UNITED STATES PATENT OFFICE.

JULIUS E. PITRAT, OF GALLIPOLIS, OHIO.

PRICE-SCALE.

SPECIFICATION forming part of Letters Patent No. 341,166, dated May 4, 1886.

Application filed August 11, 1885. Serial No. 174,126. (No model.)

To all whom it may concern:

Be it known that I, JULIUS E. PITRAT, a citizen of the United States, residing at Gallipolis, in the county of Gallia and State of Ohio, have invented certain new and useful Improvements in Couplings for Scales; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to certain new and useful improvements in scales, and has for its object to provide means whereby the price-scales described in my Patent No. 314,717 may be attached to any ordinary platform-scales, so that the money value of a substance at any given price per pound placed on the platform of the scale can be ascertained without having recourse to arithmetical computation; and to this end and to such others as the invention may pertain it consists in the peculiar combination and novel construction and arrangement of the parts hereinafter more fully described, and pointed out in the claims.

In the accompanying drawings, which form a part of this specification, Figure 1 is a top plan view, and Fig. 2 is a side elevation, of my improvement.

Referring to the drawings by letters, A represents a suitable base which may be of any desired form.

B is a carriage, which may also be of any preferred form. This carriage is constructed to be moved back and forth on the base A, and is preferably mounted upon wheels *a*, although it may slide in grooves, as shown, if desired.

C are standards or supports arising from the carriage B, and in these standards is supported the lever D, which consists upon the right or power side of two twin branches, D' D'', and upon the left side of a single branch, D'', extending from the pivot-bar *d* at a point midway between its connection with the branches D' D'', as plainly shown in Fig. 1. The branches D' D'' of the lever are each provided with two sets of graduations, *b* *c*, and the branch D'' with two sets of graduations, *g*

e, similar to those in my patent above referred to. The branch D' is designed to be used as a balancing-beam, and receives the balance-weight E, while the branch D'' is to receive 55 the weighing-bob F, as in said patent, while the carrier G is supported by the rod *f* connecting the ends of the branches D' D''. The branch D' is simply used as a guide or lever for the weight E to slide on to counterbalance 60 the scale when adjusted to the varying prices of merchandise, as will appear further on.

H is a standard fixed to the base A, and H' is a coupler pivoted to said standard.

I is a link pivoted to the inner end of the 65 coupler H', and its upper end is knife-edged, to engage the desired notch in the branch D' of the lever. This link is kept in an upright position by means of a ballast-weight, *i*, said link and weight being made in one piece. Piv- 70 otally secured to the opposite end of the coupler H' is the link I', similar to the link I, and provided with a ballast-weight, *i'*.

J represents the beam of a platform-scale, and *j* its weighing-bob. 75

K is a pivoted bale at the free end of the beam, and L is a rod, hooked at each end, connecting the bale K with the link I' of the coupler. This rod is preferably, though not necessarily, provided with a carrier, M. 80

The operation is as follows: Suppose the article whose value is to be ascertained has just been weighed and still remains on the platform of the beam J. Move the scale carried by the carriage B so that the link I will 85 fall into the notch of the branch D', indicating the price per pound of the article being weighed. Then move the balancing-bob E along on the branch D' to the right till the branch D'' tips up and bears hard enough 90 against the link I, to maintain it in place. Next move the bob *j* of the beam J to zero, and remove all the weights from the carrier M, when the beam will go up and press upward with a force equal to the down pressure 95 exerted by said weights before being removed. The beam J being relieved of its counterbalancing-weight the load thereon will cause its free end to rise, and through the connections K, L, and I' will cause the ascent of the left 100 branch of the coupler H', which will cause a corresponding depression of the opposite end,

which, being connected to the branch D³ by the link I, will bear on the graduated beam with a force indicated in dollars and cents by the weighing-bob F when placed at the point 5 of balance.

It will be noticed that the coupler H' and the scale-beam J remain relatively fixed, whereas the carriage B and its scale are movable relative to the coupler and beam J. The position 10 of this platform varies as the price per pound of the article weighed.

When the beam J is used for weighing purposes, the carrier M is necessary, but otherwise the hooked rod L without the carrier will 15 answer the purpose as well so far as computing money value of an article placed on the platform is concerned.

I do not confine myself to the exact construction shown and described, but reserve the 20 right to vary the same so far as consistent with the spirit of my invention.

Having thus described my invention, what I claim, and desire to secure by Letters Patent, is—

25 1. The combination, with an ordinary scale-beam, of a calculating or price scale, and a coupler connecting the two, whereby the net value of the article weighed on the scale-beam is indicated on the price-scale, substantially 30 as hereinbefore set forth.

2. The combination, with a scale-beam and a price-scale, of a coupler-bar pivoted midway its ends, and links, one connecting the carrier end of the scale-beam to one end of the 35 coupler, the other connecting the price-scale to the opposite end of the coupler, substantially as described.

3. The combination of the scale-beam, a price-scale, a coupler-bar fixedly pivoted relative to the scale-beam, links connecting the 40 opposite ends of the coupler to the carrier end of the scale-beam and to the price-scale, respectively, and a movable platform or carriage supporting the price scale, whereby the latter may be shifted to correspond with the 45 price per pound of the article weighed on the scale-beam, substantially as and for the purpose specified.

4. The combination of the scale-beam, a base having a standard fixed to one end thereof, a coupler pivoted to the standard and having one end connected to the carrier end of the scale-beam, a weighted link pivotally supported by the opposite end of the coupler, a carriage movable on the base, a price-scale 50 carried thereby, and having one branch of its beam movable through the weighted link, as and for the purposes set forth.

5. The combination of an ordinary scale-beam, a base supporting a standard at one 55 end, a coupler pivoted to the standard midway its ends, a link connecting one end of the coupler to the carrier end of the scale-beam, and a price-scale supported on said base and adjustably connected with the free end of the 60 coupler-bar, substantially as and for the purposes hereinbefore specified.

In testimony whereof I affix my signature in presence of two witnesses.

JULIUS E. PITRAT.
